UNITED STATES PATENT OFFICE.

JOHN P. MARTIN, OF PITTSBURGH, PENNSYLVANIA.

WASHING MACHINE.

Application filed October 31, 1921. Serial No. 511,723.

To all whom it may concern:

Be it known that I, JOHN P. MARTIN, a citizen of the United States, residing at Pittsburgh, in the county of Allegheny and State of Pennsylvania, have invented certain new and useful Improvements in Washing Machines, of which the following is a specification.

This invention relates to washing machines, particularly washing machines for domestic use, of the type in which the clothes are washed by the action of a vertically reciprocable inverted cup or cone.

According to the present invention, I provide a machine having an outer tub or tank and preferably provided with a removable perforate clothes container therein. The clothes are washed by the action of a vertically reciprocable cone having means associated therewith for varying the pressure inside the cone during the washing operation in such manner as to wash the clothes more efficiently, I believe, than machines of the same general type employing the inverted cone or so-called "vacuum cup." The cone or cup is preferably reciprocated through a hinged top for the tub, and the operating mechanism for the cone and its associated parts are preferably carried by the top or cover.

The primary objects of my invention are to provide a washing machine of the reciprocable cup or cone type having an improved cup or cone construction with means for varying the pressure therein at different positions and to provide an improved operating means therefor.

My invention may be readily understood by reference to the accompanying drawings which illustrate an embodiment of my invention, and in which:

Fig. 1 is a side elevation of a machine constructed in accordance with my invention;

Fig. 2 is a detail view showing a part of the cone operating mechanism;

Fig. 3 is a section through a portion of the machine showing the cone and its parts in raised position;

Fig. 4 is a vertical transverse section through Fig. 1;

Fig. 5 is a section on line V—V of Fig. 4;

Fig. 6 is a detail view showing in section the top of the tub;

Fig. 7 is a section on line VII—VII of Fig. 1, but on a larger scale;

Fig. 8 is a detail showing a section on line VIII—VIII of Fig. 4;

Fig. 9 is a similar view on line IX—IX of Fig. 4;

Fig. 10 is a somewhat diagrammatic view of a modification.

In the drawings, 5 represents a tub of sheet metal or other suitable material having a bottom 6 which is sunken or inclined towards a central outlet 7 leading into drain pipe 8 in which is a valve or faucet 9.

The tub 5 is supported in a frame of suitable construction, such as that shown, and which comprises four vertical channel irons 10 having their lower end portions united by a spider, or horizontal frame 11. On the lower ends of the vertical legs 10 are castors 12. The upper ends of the legs 10 are secured to the tub 5. Riveted or bolted to two of the legs 10 at the front of the machine is a connecting frame member 13 which serves as a support for a wringer, as hereinafter described.

At each side of the tub and extending rearwardly of the frame member 13 are frame members 14 which are also secured to the tub and to the legs 10. They are each provided with a rearwardly projecting arm 15 which is curved upwardly, as shown in Fig. 1. At the ends of these arms are bearings 16 through which extends a shaft 17.

The cover for the tub, designated by the numeral 18, is preferably made of wood. Bolted to its upper surface is a metal casting 19 having rearwardly extending arms 20 journaled at 21 on the shaft 17. This provides a hinge for the top, so that it can be swung vertically to give access to the interior of the tub.

Within the tub 5 is a removable clothes tub or receptacle 22, which is preferably formed of sheet metal. The lower part of the receptacle is cylindrical and is perforated over its entire area, as is also the bottom 23. The upper part of the inner tub or receptacle need not be perforated, and is preferably flared outwardly, as shown, its upper edge extending over the edge of the tub 5, as shown in Fig. 6. The cover 18, therefore, serves to hold the receptacle 22 against movement when the cover is closed.

Extending through the cover 18 and the casting 19 is hollow shaft 25, the upper end 110

of which passes through a guide member 26 supported on depending legs 27. Legs 27 are bolted to uprights 28 on the casting 19. Extending parallel with shaft 25 are two 5 guide rods 29, one at each side of the shaft, which have their lower end screwed or otherwise rigidly connected to the casting 19. Adjustably fixed to the shaft 25 is a cross 10 head 30, having set screws or other means therein for fixing it to the shaft. The cross head has openings therein through which the guide rods 29 are slidably passed, and at the ends of the cross head are trunnions or pins to which are pivotally connected links or 15 connecting rods 31 and 31'.

Rotatably carried in bearings 32 in uprights 28 and in bearings 33 in uprights 34 are horizontal shafts 35 and 35', one being located at each side of the central vertical 20 shaft 25. Shafts 35 and 35' have cranks 36 and 36' respectively, which are of the same length. These cranks 36 and 36' carry pins to which are connected the connecting rods 31 and 31' respectively. Connecting rods 25 31 and 31' are of the same length. Upon rotation of shafts 35 and 35', a reciprocable motion is transmitted to the vertical hollow shaft 25. For reasons hereinafter pointed out, shafts 35 and 35' rotate in opposite 30 directions, but since the connecting rods 31 and 31' are of equal length, the shaft 25 can be reciprocated. Lubricant may be applied to the guide rods 29 to enable cross head 30 to slide more freely thereon.

35 Within the hollow shaft 25 and reciprocable relatively thereto is a shaft 40 which extends the length of shaft 25. Shaft 25 is slotted at 41 and surrounding the shaft 25 around the slotted portion thereof is a second 40 cross head 42 which is also slidably guided on guide rods 29. The cross head, as shown in Fig. 9, is provided with a transversely extending pin or bolt 43 which passes through slots 41 in the hollow shaft 25 and 45 through an opening in the shaft 40.

A pitman or connecting rod 44 is connected with the pin 43. The lower end of the connecting rod 44 is pivotally connected with a crank 45 on a shaft 46 journalled in 50 bearings 47 and 48 in upright portions on the casting 19. Crank 45 is longer than cranks 36 and 36' and is disposed in a plane at right angles thereto. In order that the mechanism is sufficiently powerful and yet 55 compact, it is necessary that the circle through which the outer end of crank 45 moves intersects the path of travel of the cranks 36 and 36'. Cranks 36 and 36' are so arranged that when the end of crank 45 60 is at one of the points of intersection, as in the position in Fig. 7, the two cranks 36 and 36' will be 180 degrees from each other, and the crank whose path of travel is being intersected will be 180 degrees from the point 65 of intersection. As it is contemplated that

the cranks be moved in synchronism and that cranks 36 and 36' revolve in opposite directions, the cranks 36 and 36' will always be removed 180 degrees from their respective points of intersection when the crank 45 is 70 at the respective point of intersection, and collision is thereby avoided.

As shown in Fig. 7, the end of crank arm 45 is in intersection with the path of crank 36, but crank 36 is turned so that its end 75 is 180 degrees removed from this point. The end of crank 36', however, is at the point of intersection with the path of crank 45, but crank 45 is turned so that its end is away from this point. When crank 45 has turned 180 degrees, the other cranks will also have turned through a half circle. Rotation of crank 45 effects a reciprocation of rod 40. Because the crank 45 is longer than cranks 36 and 36', the inner shaft will move relatively to the outer one. 85

For driving the cranks to reciprocate shafts 25 and 40, an electric motor 50, or other suitable source of power, is employed. It is preferably mounted on the spider or 90 horizontal frame 11. The motor 50, through worm gearing 51, drives a horizontal shaft 52 supported in bearings 53. On each end of the shaft are miter gears 54 and 55. Miter gear 54 meshes with gear 56 on vertical 95 shaft 57 carried in bearings 58. The upper end of shaft 57 has a bevel gear 59 which meshes with a similar gear 60, which is loose on the shaft 17. A clutch of any simple construction is shown at 61 for connecting shaft 100 17 into driving relation with gear 60. Near each end of shaft 17 and keyed thereto are bevel gears 62 and 62'. An inclined shaft 63 journalled at 64 in suitable bearings on the castings is provided near one side of 105 the machine, and it has a bevel gear 65 meshing with gear 62 on its lower end and a gear wheel 66 meshing with gear wheel 67 on shaft 35 on its upper end. On the other side of the machine is a similar arrangement of mechanism for driving shaft 35' and comprising inclined shaft 63' in journals 64' having gear wheels 65' and 66' thereon, the latter meshing with gear wheel 67' on shaft 35'. This arrangement of gearing, as shown in Fig. 7, will drive the shafts 35 and 35' in opposite directions, gear 67' being reversed to gear 67. 115

Fixed to the shaft 17 is another bevel gear 68 and at 69 is a short vertical shaft having 120 a gear 70 at its lower end meshing with gear 68. The upper end of shaft 69 has a miter gear 71 coacting with a similar gear 72 on the end of the horizontal shaft 46 which carries crank 45.

With the arrangement of gears as shown, the operation of the cranks can be readily controlled through clutch 61 without stopping the motor 50. The top of the tub may be swung through an arc vertically to open 130

and close the tubs, the miter gears permitting of such movement.

Carried on the lower end of hollow shaft 25 is the clothes washing device. It preferably comprises a cap 75 rigidly secured to the shaft 25 from which depends a cylinder 76 of suitable construction, preferably made of brass or of other metal lined with brass. Secured to the cylinder 76 between the ends 10 thereof is an inverted cone shaped cup 77. At 78 is a perforated disk which surrounds the outside of cylinder 76 and connects to the inside of cone 77 and which serves to more rigidly secure the cup in position, the 15 cup or cone being relatively large. The cylinder 76 above the top of the cone is perforated, an annular series of perforations being indicated at 79. Similar perforations are provided at 80 below the point where the 20 cone attaches. The bottom of the cylinder is preferably closed by a perforated cap 81 screwed to the bottom thereof.

Within the cylinder is a plunger or piston 82 which is rigidly carried on the end of shaft 40. As shown in Fig. 4, the piston is at its lowermost position in the cylinder 76 when the cone 77 is in its lowermost position in the tub. As the cylinder 76 and cone 77 rise, piston 82 rises also but at a greater 30 rate of speed and a greater distance, owing to the crank 45 being larger than crank 36 and 36', until the piston is in the top of the cylinder, when the cone is in its uppermost position as shown in Fig. 3.

It is contemplated that a clothes wringer 35 also be driven from the motor 50. For this purpose, miter gear 55 is provided on shaft 52. The miter gear 55 meshes with two miter gear wheels 85 and 85' loosely carried 40 on a vertical shaft 86 journalled in bearings 87 at its lower end and journalled at its upper end in bearings 88 in the frame member 18 hereinbefore described. A clutch is provided at 89, which clutch has a neutral position and a position for engagement with each of gears 85 and 85', so that the shaft 86 can be driven in opposite directions.

The wringer is designated at 90 and is of 50 any known or preferred construction, and is mounted to swing about shaft 86 to different positions relatively to the tub, as shown.

In operation, the lid or cover 18 is opened and the clothes are placed in the perforated receptacle 22. As the machine will sometimes stop with the washing element or cone in its lowermost position, in which position the tub cannot be swung open, a crank 91 is provided at one end of shaft 17 for rotating it by hand. The crank preferably turns 55 the shaft 17 through a ratchet 92 in such manner that the crank need not rotate when the machine is operating.

After placing the clothes in the receptacle and filling the tub partly full of soapy 60 water, the lid is closed, and the motor

started. Clutch 61 is shifted to drive the various cranks, 36, 36', and 45 through the gearing hereinbefore described. Such motion of the cranks reciprocates the shafts 25 and 40, moving the respective elements carried thereby. Assuming that the cranks 36 and 36' are four inches long, cylinder 76 and cone 77 will move eight inches; and if crank 45 is six inches long, plunger or piston 82 moves twelve inches, or has a movement relatively to the cylinder of four inches. 75

When the cone is in its uppermost position, as hereinbefore stated, the top of the cylinder 76 should be above the water a few inches and ports 79 open to the atmosphere. 80 The bottom of the cone should, however, be under or at the surface of the water. As the cone descends, plunger 82 descends, compressing the air in cylinder 76 and forcing it out openings 80 into the cone through perforations in disk 78, and through the bottom of the cylinder. Some of the air will escape around the edge of the cone. The cone is thus maintained full of air under pressure during the greater portion of its downward 85 movement, and the air in the cone, as well as the edges of the cone act to force or squeeze the clothes against the bottom of the inner tub or receptacle, and to squeeze the water out of the clothes. Just the instant, 90 however, before the cone reaches its lowermost position, the piston 82 will move past ports 80 and relieve the pressure in the cone, and atmospheric pressure will momentarily 95 be restored. This pressure will be maintained for the instant the cone is in the lowest position. Then, as it starts to move upward, the piston 82 also moves upward, closing ports 80 from communication with the atmosphere and creating a suction or decrease in pressure in the cone. 100

The suction of the cone on the clothes tends to lift them away from the bottom of the inner tub or perforated receptacle, at 110 the same time causing the water to be drawn back into the lower part of the perforated receptacle and through and into the clothes. The action is, therefore, in my opinion much more efficient than in the type of machine heretofore made using inverted cones or cups 115 in which the pressure remained the same, the cups merely moving up and down in the tub, serving to pack the clothes down more or less, but not lifting them away from the bottom of the tub. When the piston 82 has 120 risen above ports 79, atmospheric pressure will be restored inside the cone, and any water which may have been sucked up into the cone will drop. The piston 82 acts, therefore, as a valve for opening and closing ports 79 and 80, as well as a compression and suction creating means. The action 125 of the washing element, therefore, is to force the water and air back and forth through the clothes, and keep them from 130

packing. Lubricant need only be applied to the guide rods 29, and, therefore, shaft 25 can be kept free of grease and dirt.

- In Fig. 10 I have shown a modification 5 which is especially adapted for use in hand washers where mechanism of the type just described is not practical. In this figure, 100 indicates an inverted hollow cup or cone carried on a vertically reciprocable rod 101. 10 The upper end of rod 101 is slidably passed through a vertically movable cross head 102, and has a nut or head 103 at its upper end. Carried on shaft 101 is a washer or abutment 104, and interposed between the abutment 15 and the cross head is a relatively stiff compression spring 105. Carried by the cone 100 is a cylinder 106 having its upper and lower ends open. In the lower part of the cylinder is a check valve 107 that opens 20 outwardly. At 108 is a valve that opens inwardly and attached to valve 108 is a vertical rod 109 guided in an arm 110 on shaft 101 and normally urged upwardly to maintain the valve seated by spring 111. The 25 upper end of rod 109 terminates a short distance below cross head 102.

In operation, vertical movement of cross head 102 serves to reciprocate rod 101 and cone 100, downward movement being transmitted 30 through spring 105, which normally allows of no relative movement between the cross head and shaft. As the cone 101 is forced down into the water, the air contained therein is trapped and compressed to press 35 against the clothes in the receptacle in which the washer operates. When the cone nears the bottom of the tub, however, it encounters the resistance offered by the clothes or the bottom of the receptacle, and cross head 102 compresses spring 105, moving relatively to 40 shaft 101. A slight relative movement of cross head 102 allows it to push down on rod 109 to open valve 108 to thereby open the cone to atmospheric pressure, and permit the 45 water to seek its level in the cone. Upon the upward movement of cross head 102, rod 109 moves up, due to the action of spring 111, seating valve 108. On the upward movement of cone 101, check valve 107 closes and 50 the cone is then sealed against atmospheric pressure, and the water is sucked up with the cone. When the cone emerges from the water, any water held therein by suction drops down. The same results, therefore, 55 are obtained by this construction as by the motor driven mechanism hereinbefore described, but the action is not so efficient.

Obviously, various other valve actuating mechanisms might be used and the construction shown in Fig. 9 might also be used in a motor driven device.

Various changes in the construction and arrangement of parts may be made in the invention within the scope of the appended 65 claims.

I claim:

1. A washing machine including a tub, a washing element in the tub comprising a vertically reciprocable inverted hollow body, and means coacting therewith for increasing the air pressure in the body on its downward movement and for drawing air out of the body on its upward movement and for restoring atmospheric pressure at the extremities of each movement. 70

2. A washing machine including a tub, a washing element reciprocable vertically within the tub and comprising an inverted cup member and a cylinder projecting into the cup member, said cylinder having a port 80 communicating with the interior of the cup member and one above said cup member communicating with the atmosphere, a plunger in said cylinder movable past the ports arranged to vary the pressure within the cup member, and means for effecting the operation of the cup member and plunger. 85

3. A washing machine including a tub, a washing element reciprocable within the tub and comprising an inverted cup, means for reciprocating the cup, a cylinder in the cup communicating with the cup, a piston in the cylinder, and other mechanical power operated means for operating the piston. 90

4. A washing machine including a tub, a hollow shaft extending into the tub, a cylinder on the hollow shaft, an inverted cup into which the cylinder projects, a piston in the cylinder, a second shaft with said hollow shaft on which the piston is carried, means for reciprocating the hollow shaft, and means for reciprocating the second shaft relatively thereto to effect a pumping action of the piston in the cylinder. 95

5. A washing machine comprising a supporting frame, a tub within the supporting frame, a hinged cover for the tub arranged to be opened and closed, a shaft passing through the cover and having an inverted cup at its lower end, pumping means communicating with the cup through passages for increasing the pressure in the cup on its downward stroke and for decreasing the pressure in the cup during its upward stroke, and operating mechanism on the 105 cover for reciprocating the shaft and means for operating the pumping means. 110

6. A washing machine comprising a supporting frame, a tub within the supporting frame, a hinged cover for the tub arranged to be opened and closed, a shaft passing through the cover and having an inverted cup at its lower end, means for increasing the pressure in the cup on its downward stroke, means for decreasing the pressure in the cup during its upward stroke, operating mechanism on the cover for reciprocating the shaft and the pressure varying means, a driving motor on the frame, and gearing between the motor and operating mechanism 120 125

for driving the latter, said gearing being so arranged as to permit of the opening and closing of the tub.

7. A washing machine comprising a frame, a tub on the frame, a hinged cover for the tub arranged to be opened and closed, a hollow shaft extending through the cover, a cylinder and inverted cup at the lower end thereof, a crank mechanism on the cover for reciprocating the hollow shaft, a second shaft inside the hollow shaft, a piston on the lower end thereof and within said cylinder, a second crank mechanism for driving the second shaft in such manner as to effect a relative movement between the cylinder and piston, a motor for driving said crank mechanisms, and a supplemental hand operated driving means for moving the parts to position to enable the cover to be opened.

10. A washing machine comprising a frame, a tub on the frame, a hinged cover for the tub arranged to be opened and closed, a hollow shaft extending through the cover, a cylinder and inverted cup at the lower end thereof, a second shaft inside the hollow shaft, a piston on the lower end thereof and within said cylinder, a second crank mechanism for driving the second shaft in such manner as

15 to effect a relative movement between the cylinder and piston, and means for driving said crank mechanism.

8. A washing machine comprising a frame, a tub on the frame, a hinged cover for the tub arranged to be opened and closed, a hollow shaft extending through the cover, a cylinder and inverted cup at the lower end thereof, a second shaft inside the hollow shaft, a piston on the lower end thereof and within said cylinder, a second crank mechanism for driving the second shaft in such manner as

20 to effect a relative movement between the cylinder and piston, and means for driving said crank mechanism.

25 9. A washing machine comprising a frame, a tub on the frame, a hinged cover for the tub arranged to be opened and closed, a hollow shaft extending through the cover, a cylinder and inverted cup at the lower end thereof, a second shaft inside the hollow shaft, a piston on the lower end thereof and within said cylinder, a second crank mechanism for driving the second shaft in such manner as

30 to effect a relative movement between the cylinder and piston, and means for driving said crank mechanism.

35 10. A washing machine comprising a frame, a tub on the frame, a hinged cover for the tub arranged to be opened and closed, a hollow shaft extending through the cover, a cylinder and inverted cup at the lower end thereof, a second shaft inside the hollow shaft, a piston on the lower end thereof and within said cylinder, a second crank mechanism for driving the second shaft in such manner as

40 to effect a relative movement between the cylinder and piston, and means for driving said crank mechanism.

45 11. A washing machine comprising a frame, a tub on the frame, a hinged cover for the tub arranged to be opened and closed, a hollow shaft extending through the cover, a cylinder and inverted cup at the lower end thereof and within said cylinder, a second shaft inside the hollow shaft, a piston on the lower end thereof and within said cylinder, a second crank mechanism for driving the second shaft in such manner as

50 to effect a relative movement between the cylinder and piston, and means for driving said crank mechanism.

55 12. A washing machine comprising a frame, a tub on the frame, a hinged cover for the tub arranged to be opened and closed, a hollow shaft extending through the cover, a cylinder and inverted cup at the lower end thereof and within said cylinder, a second shaft inside the hollow shaft, a piston on the lower end thereof and within said cylinder, a second crank mechanism for driving the second shaft in such manner as

60 to effect a relative movement between the cylinder and piston, and means for driving said crank mechanism.

65 13. A washing machine comprising a frame, a tub on the frame, a hinged cover for the tub arranged to be opened and closed, a hollow shaft extending through the cover, a cylinder and inverted cup at the lower end thereof and within said cylinder, a second shaft inside the hollow shaft, a piston on the lower end thereof and within said cylinder, a second crank mechanism for driving the second shaft in such manner as

70 to effect a relative movement between the cylinder and piston, and means for driving said crank mechanism.

75 14. A washing machine comprising a frame, a tub on the frame, a hinged cover for the tub arranged to be opened and closed, a hollow shaft extending through the cover, a cylinder and inverted cup at the lower end thereof and within said cylinder, a second shaft inside the hollow shaft, a piston on the lower end thereof and within said cylinder, a second crank mechanism for driving the second shaft in such manner as

80 to effect a relative movement between the cylinder and piston, and means for driving said crank mechanism.

85 lower end thereof, a crank mechanism on the cover for reciprocating the hollow shaft, a second shaft inside the hollow shaft, a piston on the lower end thereof and within said cylinder, a second crank mechanism for driving the second shaft in such manner as to effect a relative movement between the cylinder and piston, a motor for driving said crank mechanisms, and a supplemental hand operated driving means for moving the parts to position to enable the cover to be opened.

90 10. A washing machine comprising a tub, a washing element reciprocable within the tub and comprising an inverted hollow cup, means for effecting the reciprocation thereof, and pump means communicating with the cup through ports and with the atmosphere through another series of ports for creating a pressure above atmospheric pressure in the cup during the downward movement thereof and for restoring atmospheric pressure when the hollow cup is in its lowermost position, said means also creating a suction therein during its upward movement and restoring atmospheric pressure when the hollow cup has reached its uppermost position.

95 11. A washing device comprising an inverted hollow cup adapted to be reciprocated in a tub, means by which the hollow cup may be reciprocated, and a valve means for closing said hollow cup against the escape of air therefrom during a portion of its downward movement and for permitting the escape of air therefrom when it is at its downward limit, the valve means also acting to prevent the entrance of air into the cup when immersed and during a portion of its upward movement.

100 In testimony whereof I hereunto affix my signature.

JOHN P. MARTIN.
